COMBINED SAW HANDLE AND SQUARE

Maurice Elmo Peebles, Kingsland, Ga., assignor
to Kingsland Saw Works, Inc., a corporation of
Georgia

Application April 30, 1947, Serial No. 744,943

3 Claims. (Cl. 33—112)

1

This invention relates to a combined saw and square and is an improvement over the construction embodied in my copending application Serial No. 744,942, filed April 30, 1947.

An object of this invention is to provide, in combination with a saw handle, an extendible square which is adapted to be normally seated and latched in a flush position on one side of the saw handle.

Another object of this invention is to provide, in combination with a saw handle, a square which is hingedly secured on one edge thereof to the handle, and is spring-pressed to an extended position, being normally latched in inoperative position in a pocket or recess of right angular configuration, which is formed in the handle.

Another object of this invention is to provide, in combination with a handle, an extendible square which will not interfere with the normal use of the handle and the saw, being normally seated flush with one surface of the handle.

A further object of this invention is to provide an improved means for effecting extension of the handle, the means including a tensioned spring which has one end thereof fixed relative to the pivotal mounting for the square, and the other end fixed to an adjacent portion of the square, the pivotal mounting being secured at one side thereof to the upper edge of the handle and comprising an elongated hinge leaf.

With the above and other objects in view, my invention consists in the arrangement, combination and details of construction disclosed in the drawings and specification, and then more particularly pointed out in the appended claims.

In the drawings,

Figure 1 is a detail side elevation of a saw handle having a square mounted thereon.

Figure 2 is a top plan view of the handle and square.

Figure 3 is a sectional view taken on the line 3—3 of Figure 1.

Figure 4 is a fragmentary sectional view taken on the line 4—4 of Figure 1.

Figure 5 is a plan view of the square and hinge mounting removed from the saw handle.

Figure 6 is a fragmentary sectional view taken on the line 6—6 of Figure 2.

Figure 7 is a fragmentary sectional view taken on the line 7—7 of Figure 6.

Figure 8 is a fragmentary sectional view taken on the line 8—8 of Figure 1.

Figure 9 is a fragmentary sectional view taken on the line 9—9 of Figure 8.

2

Referring to the drawings, the numeral 10 designates generally a conventional saw blade formed with saw teeth 11 on one edge thereof and with a back edge 12 which may be formed as a straight edge.

A saw handle generally designated as 13 is secured by fastening members 14 to the rear of the blade 10, the handle 13 being provided with a slot 15 within which the rear end of the blade 10 is adapted to seat. The handle 13 includes a finger opening 16 through which the fingers of the hand are adapted to be extended, and also includes a grasping element 17 which is to be grasped in the palm of the hand and by the fingers.

The handle 13 is formed with a right angle recess 18 which extends through the hand grasping portion 17 and also extends, as indicated at 19, through the upper portion of the handle. A square generally designated as 20 is adapted to be normally seated in the right angle recesses 18 and 19. The square 20 in the present instance is formed of a right angle metal square member 21 which has secured thereto a transparent right angle facing 22. The facing 22 may be secured to the metal square member 21 by adhesive means or by rivets or fastening members 23.

In order to provide for extension of the square 20 from the recesses 18 and 19, the square 20 on its upper side 24 has a hinge leaf 25 pivotally secured thereto. The hinge leaf 25 is adapted to be secured to the upper edge of the handle 13 by fastening members 26 or the like. The side 24 of the square is adapted to normally seat in the upper recess 19, whereas the opposite side 21 is adapted to seat in the recess 18.

The square 20 is spring-pressed to an extended position by means of a coil spring 28. The spring 28 has one end 29 thereof extended into the upper portion of the handle 13, and the other end thereof is formed with a curved extension 30 which is secured, as indicated at 31, to the square 20. The spring 28 has extending therethrough a pin 32 which has one end thereof extending through an eye 33 fixed relative to the hinge leaf 25. The other end of the pin 32 may also be secured relative to the hinge leaf 25 by means of a second eye 34a which is also fixed to the hinge leaf 25.

The spring 28 is adapted to be shielded by means of a shield 34 which is of substantially U-shape in transverse section, being provided with an inclined inner end wall 35, terminating at its lower end in a lug 36 which is secured by

fastening means 37 on the upper side of the hinge leaf 25. In practice, the fastening member 37 may be one of the screws 26 which secure the hinge leaf 25 to the upper or back edge of the handle 13.

The shield 34 also includes a rearwardly projecting lug 38 which extends over an upwardly projecting rear part 39 formed on the handle 13, and secured to the handle extension 39 by one or more fastening members 40. The shield or housing 34 is provided adjacent the rear thereof with a slot 41 through which the spring extension 30 is adapted to loosely engage so that the square 20 upon release thereof by release of the latching means to be hereinafter described, will be spring-pressed to an extended position relative to the handle 13.

The square 20 is adapted to be releasably latched in countersunk position in the recesses 18 and 19 by means of a spring-pressed latch generally 20 designated as 42. The latch 42 includes an elongated shank 43 which extends loosely through a cylindrical housing 44 disposed in an opening 45 formed in the lower portion of the handle 13. The shank 43 is formed at its inner end with a head 46 slidably engaging in the housing 44, and is formed at its inner end in a tapered or inclined latching bill 46 which is adapted to engage the metal square side 21, as shown in Figure 9.

The covering 22 for the square is recessed as indicated at 47 to permit the bill 46 to engage the square side 21. A spring 48 is disposed within the sleeve or housing 44 bearing at its inner end against the head 46 and the outer end of the spring 48 bears against an annular flange 49 carried by the outer end of the sleeve 44. The flange 49 is formed by crimping the outer end of the sleeve 44. The shank 43 extends outwardly of the housing 44 and has secured thereto an operating knob or button 50 which is fixed to the shank 43 by fastening means 51.

When the latch is in its latching position, the inner end of the knob or button 50 will be disposed in contacting relation with the outer end of the sleeve or housing 44. The shank 43 is held against rotation by means of an elongated bar or rod 52 which is fixed at its outer end to the knob or button 50 and loosely engages in an opening 53 formed in the handle 13 parallel with the housing 44, but offset therefrom.

The saw blade 10 may be used in the normal manner for cutting wood or the like, and when the square 20 is in its inoperative position, this square will be seated within the recesses 18 and 19 with the outer surface of the square substantially flush with the adjacent surface of the handle 13. When it is desired to use the square 20, the latching button 50 is pulled outwardly, thereby disengaging the bill or bolt 46 from the side 21 of the square. When the latching means has been moved to released position, spring 28 will swing the square outwardly and this square may then be used to square up the work piece.

By providing the spring which automatically moves the square 20 to extended position, this

square may be used in any angular position desired with respect to the handle 13. In other words, the square 20 may be swung through an arc of 180° with respect to the handle 13 and may be used at any position within this arc.

With a combined handle and square as herein-before described, any conventional saw blade may be formed into a combined saw and square as this handle may be mounted on and constructed 10 as a combined handle and square attachment for conventional saw blades.

I do not mean to confine myself to the exact details of construction herein disclosed, but claim all variations falling within the purview of the 15 appended claims.

What I claim is:

1. A combined saw handle and square comprising a handle having a recess in one side thereof, a metal square element adapted to seat in said recess having arms at right angles to each other, one of said arms being formed with half of a hinge on an edge thereof, a plate adapted to be secured to said handle and formed with half of a hinge on one edge thereof, a hinge pin for swingably connecting said half hinges, spring means carried by said plate and operatively associated with said square constantly urging said square away from seating position in said recess, and latching means carried by said handle and operatively associated with said square for holding the latter in seated position.

2. The device of claim 1 in which said spring means comprises a plurality of eyes mounted on said plate, a shaft supported by said eyes, and a coil spring formed with a plurality of convolutions encircling said shaft and having one end secured in said plate and the other end secured in said square.

3. A combined saw handle and square comprising a handle having a recess in one side thereof, a metal square element having right angle arms adapted to seat in said recess, one of said arms being formed with a piano type hinge extending the length of an outside edge thereof, a plate 45 carried by said hinge and adapted to be secured to said handle, spring means carried by said plate and operatively associated with said square constantly urging said square away from seating position and latching means operatively associated 50 with said handle and said square for holding the latter in seated position.

MAURICE ELMO PEEPLES.
